SKIP FEED MECHANISM

Charles Jacobson, New York, N. Y., assignor to
 S. & S. Corrugated Paper Machinery Co. Inc.,
 Brooklyn, N. Y., a corporation of New York

Application November 30, 1942, Serial No. 467,344

8 Claims. (Cl. 271—44)

1

My present invention relates to a blank feeding mechanism for moving blanks successively from the bottom of a stack, and more particularly to a feeding mechanism of the so-called skip-feed type.

In the manufacture of printed, slotted and creased cartons, it is necessary to pass the blanks for forming such cartons through printer-slotters or creasers in order to predetermine the fold line and the various slot formations on the carton as well as to imprint the same.

In operation, such printer-slotted and similar machines are provided with means for retaining a stack of blanks, and feeding mechanism which successively feeds out the bottom blank in the stack. Where the blanks which are to be operated on by the printer-slotted are of uniform length, then an ordinary feeding mechanism of a type which is now well known in the art may be used. Where, however, the blanks may vary widely in length, then if the feed mechanism is arranged so that it will accommodate itself to the longest blank, a great deal of added material is required for the machine; and the machine, especially the stack supporting and feeding portion thereof, will occupy an excessive amount of space.

It is therefore preferred to construct the machine so that relatively short blanks may be fed by successive feeding operations. Where, however, the blanks are much longer in length, then should the feeding operation take place on each cycle of movement of the feed mechanism a blank may not be cleared through the printer-slotted mechanism before the next blank is fed in on top of it.

Accordingly, it becomes necessary to devise a simplified skip-feed device which may selectively be put into operation or disconnected. The skip-feed device is used when blanks of greater length are to be fed through the mechanism.

In this case, the skip-feed mechanism is adjusted so that the feeding device will operate upon every other cycle and will be disengaged from operating at intermediate cycles. This will permit a long blank which is fed out from the stack to be cleared through the mechanism before the next blank is fed in. That is, when the blanks are fed every other cycle, an extra long blank will be grasped by the feed roll and passed into the printer-slotted mechanism before the next blank reaches the feed rolls.

The skip-feed mechanism obviously must be adjustable or rather disconnectable and connectible so that when short blanks are fed through the mechanism thus permitting a feeding operation

2

during every cycle of the feeding mechanism, the skip-feed will not be operative.

An important object of my invention is to provide a novel simplified skip-feed mechanism for feeding out successive blanks from the bottom of a stack at every other cycle of the feeding mechanism.

Skip-feed mechanisms are not per se new in the art. However, in actual operation, such mechanisms have depended upon complicated apparatus which lifted the stacks out of feed engaging position during one cycle, and dropped the entire stacks into feed engaging position during the next cycle.

15 In my present invention, the skip-feed is obtained by varying the path of travel of the feeding mechanism during successive cycles. When the skip-feed mechanism is connected to the feeding apparatus then the feeding apparatus will be moved its full length to engage a blank in a stack during one cycle; and during the next cycle will be moved only partly back so that it will not engage the back end of the stack during the next cycle. During the following cycle, the skip-feed mechanism will now move back once more to blank engaging position. The mechanism is also so arranged that the skip-feed operation can readily be dispensed with by a simple adjustment and the feeding mechanism may move back its full travel to engage the back end of the lowest blank in the stack during each cycle.

30 The skip-feed mechanism is obtained by the utilization of a collapsible connecting toggle between the operating apparatus for the skip-feed and the skip-feed member itself. When the toggle is extended, the feeding apparatus is given its full length of travel. When the toggle is partly collapsed, the skip-feed mechanism is given only a partial travel, and thus does not reach back far enough to engage the stack.

35 The adjustment apparatus of my invention is so arranged that when the skip-feed mechanism is operative, the toggle will alternately be extended and collapsed during alternate cycles of the feeding mechanism.

40 A further object of my invention therefore is to provide in connection with a blank feeding mechanism, a connecting member for the feeding mechanism, said connecting member being automatically adjustable in length.

45 Still another object of my invention is to provide between the operating members for feeding apparatus and the feeding apparatus itself a toggle connecting element which may selectively be collapsed or straightened to provide

different paths of travel for the feeding mechanism.

These and many other objects of my invention will become apparent and where they are not apparent will be pointed out in the following description and drawings in which:

Figure 1 is a schematic view in perspective of my novel skip-feed mechanism.

Figure 2 is a cross sectional view of my novel feeding mechanisms showing the operation of my skip-feed, the said view being taken on line 2-2 of Figure 3 looking in the direction of the arrows.

Figure 3 is a top plan view partly in cross section taken along line 3-3 of Figure 2 looking in the direction of the arrows.

Figure 4 is a cross sectional view taken along line 4-4 of Figure 3 looking in the direction of the arrows.

Figure 5 is a view corresponding substantially to that of Figure 2 showing a different position of the feeding apparatus.

Figure 6 is a view corresponding substantially to that of Figure 5 showing another position of the feeding apparatus.

Figure 7 is a cross sectional view taken on line 7-7 of Figure 3 looking in the direction of the arrows.

Figure 8 is a cross sectional view taken on line 8-8 of Figure 3 looking in the direction of the arrows.

Figure 9 is a cross sectional view taken on line 9-9 of Figure 3 looking in the direction of the arrows.

Figure 10 is a view corresponding to that of Figure 9 showing a different position of the operating element.

Referring now to the schematic view of Figure 1 and the cross sectional views of Figures 2 and 3, the printing-slitting apparatus is provided with a principal drive shaft 20 carrying the principal driving gear 21.

Any suitable source of power may be connected to the drive shaft 20 for driving the mechanism. The principal drive gear 21, through the various gear trains 22, 23, 24, 25, 26, and 27 and other gears not shown, drives the feed rollers 30 and 31, the upper and lower printing rollers 32 and 33, the additional feed rollers 34 and 35, and any other rollers or shafts which it is necessary to operate in order to obtain appropriate printing, slitting, creasing, or other similar operations upon the blank which is fed between the said rollers.

The face of the main drive gear 21 is provided with a pin 40 secured thereto in any suitable manner at a distance from the center of rotation thereof, and carrying rotatably mounted thereon the slide block 41.

The slide block 41 is captured by the crank arm 42 which is provided with a longitudinal slot 43 within which the slide block 41 may slide. The sides of the slot 43 are so arranged as to retain the slide block 41 against unintentional removal therefrom.

It will now be obvious that rotation of the gear 21 resulting in corresponding rotation of the pin 40 will in effect cause the slide block 41 alternately to move from one side of the shaft 20 to the other.

Since the crank arm 42 is keyed to the shaft 45, and since the lower end of the crank arm is pivotally fixed in definite relation to the shaft 20, the alternate movement of the side block 41 from side to side of the shaft 20 will result in the

alternate swinging from right to left of the crank arm 42. This will result in alternate rotation of the shaft 45 clockwise and counterclockwise, then clockwise once more.

Crank arm 47 is keyed to the shaft 45 and hence rotatable therewith. Therefore, the alternate rotation in one direction and then in the other of the shaft 45 will produce a corresponding oscillation of the crank arm 47, the said crank arm 47 oscillating back and forth in synchronism with the crank arm 42.

The free end of the crank arm 47 is pivotally connected at 48 to the toggle link 49 which is by the knee pin 50 connected to the other toggle link 51 which in turn is at 52 pivotally connected to the depending lug 53 of the feed carrying arm 55. The feed carrying arm 55 is provided with a plurality of vertical rollers 56, 56 adapted to ride on the rails 57 on the bed of the apparatus. The feed arm is also provided with a plurality of horizontal rollers 58, 58 adapted to bear against the vertical rails 60 on the bed of the apparatus. Both the rails 57 and 60 are supported on the frame platform 61.

It will be obvious that the feed arm 55' is connected to the shaft 45 in exactly the same manner as is the feed arm 55 and is operated thereby likewise in the same manner.

It will now be clear that as the shaft 45 rotates clockwise thus rotating the crank arm 47 clockwise, then through the toggle 49-51, this clockwise rotation of the crank arm 47 will be translated into a full movement toward the right of the feed carrying arm 55. This will be so as long as the knee pin 50 of the toggle 49-51 is supported. Likewise movement to the left of the crank arm 47 will, through the toggle 49-51, pull the feed carrying arm 55 to the left to result in a feed out of the blank which has been engaged by the feeding element 65 on the feed arm 55.

The knee pin 50 of the toggle is supported and controlled by the link 70 which is pivoted thereto at one end. The opposite end of the link is pivoted on the pin 71 to the arm 73 of the bell crank lever 74.

Bell crank lever 74 is provided with an opening 75 which is freely mounted on the shaft 45 and hence is rotatable with respect thereto, and not affected by the rotation thereof.

The opposite arm 76 of the bell crank lever is pivotally connected by the pin 77 to the control lever 78. Control lever 78 is provided with the ring bearings 80 at the opposite end thereof, the said ring bearings being formed from a half-circular section 81 integral with the lever 78, and an additional half-circular section 82 bolted at 83,83 to the first circular half-section 81 thus forming a ring bearing which embraces the eccentric 90.

The eccentric 90 as may readily be seen from Figure 3, is provided with annular flanges 91, 91 which embrace the ring bearing 80 and maintain the same in position thereon. The eccentric 90 is keyed to and rotatable with the shaft 95 which carries at its outer end the gear 96. Shaft 20 carries at its inner end gear 97 which through the adjustable idler gear 98 drives the gear 96, and hence rotates shaft 95 to cause rotation of the eccentric 90.

Figures 2 and 8 illustrate the position of the elements when the eccentric member 90 is fixed against rotation and the adjustable idler gear 98 has been moved out of engagement with the gear

97 so that no motion may be transmitted from the shaft 20 to the shaft 95.

In Figure 1 it should be assumed for the purposes of the present discussion that gear 98 has been moved out of engagement with gear 97 and likewise for purposes of the present discussion, the same assumption should be made with respect to Figure 3.

It will be obvious, especially from Figure 3 (and also Figures 7 and 8) that the gear 98 is mounted on a stub-shaft 100, which in turn is rotatably carried in the bearing 101 at the end of the adjusting arm 102. Adjusting arm 102 is provided with an opening 103 which is mounted on the outer end of shaft 95, but is really rotatable thereabout.

As seen in Figure 3, the adjustment arm 102 need not necessarily be mounted directly on the shaft 95, but may be mounted on a sleeve 105 surrounding the shaft 95 but spaced therefrom and being supported by bolts 106 which passes through a flange 107 on the said sleeve and into the bearing housing 108.

The bearing housing 108 for shaft 95 as will be seen in Figure 3, also comprises a gear housing for the gear train 97, 98 and 96.

When the handle 110 at the end of the arm 102 is therefore pushed down, the said shaft 100 carrying the gear 98 is lifted up at the opposite end; thus as shown in Figure 8, disengaging the gear 98 from the gear 97, so that the shaft 95 is not driven.

The gear 98 is moved out of engagement when no skip-feed operation is desired, and when it is desired that the feeding arm 55 and feed apparatus 65 at the end thereof engage a blank from the stack during each feed cycle. In this non-skip feed arrangement, it is desirable that the eccentric 90 be in the position shown in Figures 1 and 3, where the narrowest portion thereof is on the side towards the feeding apparatus so that the adjustable arm 78 has been retracted to its greatest extent away from the feeding apparatus 55. In order to insure that this position is secure, when the handle 110 of the adjustment arm 102 is depressed to disengage the gear 98, it is desirable to lock the shaft 95 with the eccentric 90 in the position shown in Figures 1 and 3.

Accordingly, a hand wheel 120 is on the end of the shaft 121 carried in any suitable bearing on the frame and is provided with a sprocket wheel 122 carrying a chain 123 engageable with a sprocket wheel 124 on the shaft 95.

When the gear wheel 98 has been disengaged by depressing lever 110, the hand wheel 120 is then rotated until the shaft 95 has been rotated to a position where the eccentric 90 is in a position shown in Figure 3, and the shaft 95 is then locked into this position. A suitable indicator may be mounted on the end of shaft 95 for this purpose.

The locking engagement is obtained by means of the pawl 130 pivotally mounted at 131 on the frame of the machine, the end 132 of the pawl being urged upwardly by the tension spring 133 engaging the opposite arm 134 of the pawl lever (see Figure 8).

A sleeve 136 on the shaft 95 is provided with a notch 140 and the said pawl end 132 will be forced into engagement with the notch 140 when the notch moves opposite this pawl end. This condition will obtain when the eccentric 90 has been moved to the position of Figure 3.

When the skip-feed mechanism has been rendered operative once more by raising of the

handle 110 then it is necessary that the pawl arm 130 be moved to disengaged position so that the shaft 95 may freely rotate. This can be obtained by providing a roller 145 on the adjustment arm 102, the said roller 145 bearing against the arm 130 of the pawl member and pressing it down when the handle 110 has been raised, thus disengaging the pawl from the notch 140 as shown in Figure 7, and maintaining the pawl in disengaged position until the handle 110 is raised once more.

The handle 110 is provided with a locking pin 150 which is carried by an arm 153 on the frame (see Figures 3 and 8) and passes through a slot 152 in the handle.

A lock nut 155 is mounted on the end of the locking pin 150, the lock nut being provided with a handle 156. When the handle 110 has been moved to selected position, rotation of the lock nut handle 156 will lock it in such position.

Now as will be obvious from inspection of Figures 1, 2 and 3 (especially Figure 1), when the adjustable lever 78 has been pulled furthest to the left, the bell crank lever 74 has been rotated to its greatest extent counterclockwise, and consequently pin 71 has been lifted to its highest position.

Accordingly, link 70 has been lifted to its highest position, thus raising the knee pin 50. Since the knee pin 50 of the toggle 49-51 has been raised, this toggle 49-51 has been extended to its greatest extent. Now when the shaft 45 oscillates back and forth the toggle 49-51 will similarly oscillate back and forth being maintained in its extended position by the link 70 which in turn is pivotal on the pin 71.

Consequently, the feed carrying member 55 will during each cycle be pushed back to its greatest extent. When as shown in Figure 2, the feed member 65 has been pushed back to its greatest extent, it bears behind the lowest blank 160 in the stack 161, so that on the return movement it will feed this blank out between the feed rolls 30-31.

As will be obvious, the feed apparatus 65 consists of a spring member 170 which is urged upwardly and an additional raised member 171 carried by the spring member and forming an abutment 172 which is caught behind the rear end of the lowest blank in the stack when the feed mechanism is forced back.

Consequently, in this locked non-oscillating position of the adjustable arm 78, the feed mechanism will feed during every cycle and will not skip cycles.

When the handle 110 has been raised to cause the gear 98 to be engaged between gears 96 and 97, then the pawl 132 is withdrawn from locking engagement as previously described so that the shaft 95 may rotate, and the shaft 95 is caused to rotate by the gear train 97, 98 and 96. Accordingly, the eccentric 90 will now rotate. As the eccentric rotates, it will cause the adjustable lever 78 to oscillate back and forth.

During the movement of the lever 78 toward shaft 45 the bell crank lever 73 will be rotated clockwise to lower the pin 71, and hence pull down the knee pin 50 of the toggle thus collapsing the toggle 49-51 and hence shortening the distance between pin 48 and pin 52, thereby shortening the travel of the feed arm 55.

When the eccentric rotates to the opposite position where the widest side thereof is on the opposite side from the lever 78, then when the lever 78 is pulled back to the left once more the knee pin 50 of the toggle 49-51 is raised again.

The gear ratios are so adjusted that the shaft 45 will oscillate back and forth twice for each single rotation of the shaft 95. Accordingly, when the shaft 95 is rotating, then during one oscillation of shaft 45, the toggle 49-51 will be extended to its fullest extent, but during the next oscillation of the shaft 45, the toggle 49-51 will be collapsed.

When the feed mechanism is then moved back while the toggle 49-51 is collapsed, then the elements assume the position shown in Figure 4 where the blank engaging member 65 does not move to the back of the stack 161, and thus does not engage the lowest blank in the stack. Thus, when the feed arm 55 moves back and forth while the toggle 49-51 is collapsed, a waste motion is produced and no feeding occurs. Therefore when very long blanks are to be fed by the feeding mechanism, then if the blanks are of such length that one blank will not be cleared from the stack before the next blank is to be fed, the mechanism is adjusted so that the shaft 95 will be caused to rotate thus making every other oscillatory movement of the feed mechanism an idle one and thus providing for a skip-feed device.

This becomes more obvious from an inspection of Figure 4. In Figure 4 the position of the apparatus is shown with the feed mechanism pushed back to its greatest extent preliminary to the feeding operation. It will here be seen that the feed mechanism 65 has not been moved back sufficiently far to engage the back end of the lowest blank.

Thus in Figure 5 it will be seen that during the feed-out operation when the skip-feed mechanism has thus been effective, no blanks are being fed at all.

During alternate feeding strokes a feeding operation will occur as shown by the engagement of the feed mechanism 65 with the back end of the lowest blank 160 in the stack as seen in Figure 6.

The manner in which, when the skip-feed mechanism is engaged, the feed stroke is alternately lengthened and shortened should now be obvious.

It is however more fully explained in connection with the legends on Figures 9 and 10 which show the different positions of the mechanism, and particularly the different positions, collapsed and extended, of the toggle 49-51.

In the foregoing I have set forth my invention in connection with only a preferred embodiment thereof. The essence of the invention lies in the fact that a toggle connecting mechanism between the feed operating element and the feed arm itself may alternately be collapsed or extended to produce an alternate feed interpolated with an alternate waste motion.

This skip-feed mechanism may be rendered inoperative so that the toggle is extended during every stroke of the feed arm to produce successive feeding operations on successive feed arm strokes.

Many variations of the foregoing preferred embodiments of my invention should now be obvious to those skilled in the art. Accordingly I prefer to be bound not by the specific description therein but only by the appended claims.

I claim:

1. In apparatus for feeding successive blanks from the stacks, a feed arm, means for causing said feed arm to oscillate back and forth beneath said stack, means on the end of said feed arm engageable with the back end of a blank at the

bottom of said stack upon completion of the stroke of said oscillating feed arm in one direction, said means feeding said blank out from said stack on movement of said arm in said opposite direction, and means for alternately changing the degree of travel of said feed arm causing said feed arm to move to engage in blanks at the bottom of the stack in each alternate stroke and causing said feed arm to move to a position short of the back end of the blank in the bottom of the stack in each interpolated stroke.

2. In apparatus for feeding successive blanks from the stacks, a feed arm, means for causing said feed arm to oscillate back and forth beneath said stack, means on the end of said feed arm engageable with the back end of a blank at the bottom of said stack upon completion of the stroke of said oscillating feed arm in one direction, said means feeding said blank out from said stack on movement of said arm in said opposite direction, and means for alternately changing the degree of travel of said feed arm causing said feed arm to move to engage in blanks at the bottom of the stack in each alternate stroke and causing said feed arm to move to a position short of the back end of the blank in the bottom of the stack in each interpolated stroke, said last mentioned means being rendered selectively inoperative to cause said feed arm to engage a blank at each stroke thereof.

3. In apparatus for feeding successive blanks from the stacks, a feed arm, means for causing said feed arm to oscillate back and forth beneath said stack, means on the end of said feed arm engageable with the back end of a blank at the bottom of said stack upon completion of the stroke of said oscillating feed arm in one direction, said means feeding said blank out from said stack on movement of said arm in said opposite direction, and means for alternately changing the degree of travel of said feed arm causing said feed arm to move to engage in blanks at the bottom of the stack in each alternate stroke and causing said feed arm to move to a position short of the back end of the blank in the bottom of the stack in each interpolated stroke, said last mentioned means comprising an oscillatable crank arm, a toggle connection between said oscillatable crank arm and said feed arm and means for alternately collapsing and extending said toggle at alternate strokes.

4. In apparatus for feeding successive blanks from the stacks, a feed arm, means for causing said feed arm to oscillate back and forth beneath said stack, means on the end of said feed arm engageable with the back end of a blank at the bottom of said stack upon completion of the stroke of said oscillating feed arm in one direction, said means feeding said blank out from said stack on movement of said arm in said opposite direction, and means for alternately changing the degree of travel of said feed arm causing said feed arm to move to engage in blanks at the bottom of the stack in each alternate stroke and causing said feed arm to move to a position short of the back end of the blank in the bottom of the stack in each interpolated stroke, said last mentioned means comprising an oscillatable crank arm, a toggle connection between said oscillatable crank arm and said feed arm and a link connected to the knee pin of said toggle, and means for raising and lowering said link during alternate strokes of said

feed arm to alternately collapse and extend said toggle.

5. In apparatus for feeding successive blanks from the stacks, a feed arm, means for causing said feed arm to oscillate back and forth beneath said stack, means on the end of said feed arm engageable with the back end of a blank at the bottom of said stack upon completion of the stroke of said oscillating feed arm in one direction, said means feeding said blank out from said stack on movement of said arm in said opposite direction, and means for alternately changing the degree of travel of said feed arm causing said feed arm to move to engage in blanks at the bottom of the stack in each alternate stroke and causing said feed arm to move to a position short of the back end of the blank in the bottom of the stack in each interpolated stroke, said last mentioned means comprising an oscillatable crank arm, a toggle connection between said oscillatable crank arm and said feed arm and a link connected to the knee pin of said toggle, and means for raising and lowering said link during alternate strokes of said feed arm to alternately collapse and extend said toggle, said last mentioned means comprising an additional arm and a member for oscillating said additional arm, said additional arm being connected to said link for raising and lowering the same.

6. In apparatus for feeding successive blanks from the stacks, a feed arm, means for causing said feed arm to oscillate back and forth beneath said stack, means on the end of said feed arm engageable with the back end of a blank at the bottom of said stack upon completion of the stroke of said oscillating feed arm in one direction, said means feeding said blank out from said stack on movement of said arm in said opposite direction, and means for alternately changing the degree of travel of said feed arm causing said feed arm to move to engage in blanks at the bottom of the stack in each alternate stroke and causing said feed arm to move to a position short of the back end of the blank in the bottom of the stack in each interpolated stroke, said last mentioned means comprising an oscillatable crank arm, a toggle connection between said oscillatable crank arm and said feed arm and a link connected to the knee pin of said toggle, and means for raising and lowering said link during alternate strokes of said feed arm to alternately collapse and extend said toggle, said last mentioned means comprising an additional arm and a member for oscillating said additional arm, said additional arm being connected to said link by a bell crank lever.

7. In apparatus for feeding successive blanks from the stacks, a feed arm, means for causing

said feed arm to oscillate back and forth beneath said stack, means on the end of said feed arm engageable with the back end of a blank at the bottom of said stack upon completion of the stroke of said oscillating feed arm in one direction, said means feeding said blank out from said stack on movement of said arm in said opposite direction, and means for alternately changing the degree of travel of said feed arm causing said feed arm to move to engage in blanks at the bottom of the stack in each alternate stroke and causing said feed arm to move to a position short of the back end of the blank in the bottom of the stack in each interpolated stroke, said last mentioned means comprising an oscillatable crank arm, a toggle connection between said oscillatable crank arm and said feed arm and a link connected to the knee pin of said toggle, and means for raising and lowering said link during alternate strokes of said feed arm to alternately collapse and extend said toggle, said last mentioned means comprising an additional arm and a member for oscillating said additional arm, said additional arm being connected to said link by a bell crank lever, and an eccentric engageable with said oscillatable arm, said eccentric being operable to move said oscillatable arm to collapse said toggle once during each rotation thereof and likewise to move said arm to extend said toggle once during each rotation thereof.

8. In feeding apparatus for moving a blank from the bottom of a stack, an oscillatable feed arm engageable on movement in one direction thereof with the lowest blank at the bottom of the stack and operable on movement in the other direction to move said lowest blank out of the bottom of the stack, means including collapsible driving members for oscillating said feed arm back and forth, and means for selectively alternately extending and collapsing said driving means to vary the strokes of said feed arm during movement thereof to engage the back end in the bottom blank in the stack, said feed arm being moved to a position short of the back end of the bottom of the stack when said raising means is collapsed.

CHARLES JACOBSON.
